UNITED STATES PATENT OFFICE.

EVERETT S. CAMERON, OF WEST HAVEN, CONNECTICUT.

VALVE ACTION FOR EXPLOSIVE ENGINES.

1,402,478.

Specification of Letters Patent.

Patented Jan. 3, 1922.

Application filed June 18, 1920. Serial No. 389,900.

To all whom it may concern:

Be it known that I, EVERETT S. CAMERON, a citizen of the United States, residing at West Haven, in the county of New Haven and State of Connecticut, have invented a new and useful Improvement in Valve Actions for Explosive Engines; and I do hereby declare the following, when taken in connection with the accompanying drawings 10 and the characters of reference marked thereon, to be a full, clear, and exact description of the same, and which said drawings constitute part of this application, and represent, in—

15 Fig. 1, a view partly in front elevation and partly in vertical transverse section of one form which an explosive engine embodying my improved valve-action, may assume.

20 Fig. 2, a broken view partly in side elevation and partly in vertical section of a two-cylinder unit embodying my invention.

Fig. 3, a detached view in elevation of one of my improved valve-operating shafts.

25 Fig. 4, a plan view thereof.

Fig. 5, a reverse plan view thereof.

Fig. 6, a detached view in side elevation of one of the rocker-shaft bearing-sleeves.

Fig. 7, a plan view thereof.

30 Fig. 8, a detached plan view on the full scale, of one of the double, valve-operating rocker-arms.

Fig. 9, a view thereof in front elevation.

Fig. 10, a detached plan view of one of the 35 cam-arms of the rocker-shafts.

Fig. 11, a view thereof in side elevation.

Fig. 12, a plan view of one of the cams.

My invention relates to an improved valve-action for explosive engines of the type in 40 which the cam-shaft is located within the crank-case at a point directly below the crank-shaft, and therefore remote from the heat developed by the engine and where it and the parts operated by it will be amply lubri-

45 cated by the oil within the crank-case, the object being to produce a simple, compact, and durable valve-action constructed with particular reference to convenience of access and adjustment and effectiveness of operation.

50 With these ends in view, my invention consists in a valve-action for explosive engines, having certain details of construction as will be hereinafter described and pointed out in the claims.

55 In carrying out my invention, as herein

shown, I employ two, vertically arranged, valve-operating rocker-shafts 2 and 3, the former operating the two inlet-valves 4 of a two-cylinder explosive engine, and the latter operating the two exhaust-valves 5 thereof. The said shafts are mounted in long, vertically arranged, rocker-shaft bearing-sleeves 6 from the upper and lower ends of which the squared upper and lower ends of the shafts project, these long sleeves being set into and supported by the upper face of the upper half 7 of the crank-case, the removable lower half 8 of which is filled with oil which is splashed about as the engine operates. Under this construction, about one-half of the length of each sleeve is exposed above the crank-case, while about one-half of the length of each sleeve is housed within the case.

75 For so mounting the respective bearing-sleeves, each is provided about midway of its length with a suspension-flange 9 arranged at a right angle to its axis and adapted to rest directly upon the top of the upper half 7 of the crank case, each of these flanges being inwardly extended to form a fastening-lug 10 receiving a bolt 11 by means of which the flange and hence the sleeve is solidly fastened to the case. As shown, the 80 upper ends of the sleeves are reinforced by tapering radial webs 12 merging at their lower ends into the upper faces of the horizontal suspension-flanges 9. The lower ends of the sleeves are enlarged to form wide 85 aligning-bearings 13 which, when the sleeves are in place, pass downward through integral, loop-like bearings 14 cast within the lower edge of the upper half 7 of the case. The lower portions of the said sleeves, by 90 which I mean those portions thereof housed within the crank-case, are formed with a vertical range of oil-feed holes 15 through which the oil is admitted from the crank-case to the rocker-shafts 2 and 3, each of 95 which, as shown, is formed throughout its length with a spiral oil-distributing groove 16, whereby they are thoroughly lubricated throughout their entire length, the oil rising through the said grooves by capillary 100 action.

The shafts 2 and 3 are suspended from their upper ends in the sleeves 6 by means of collars 17 secured in place by pins 18 and resting upon the upper edges of sleeves, on 110 which they turn and by which the shafts are solely supported, while the sleeves in turn

are suspended in the top of the crank-case by the suspension-flanges 9, as described.

The projecting upper ends of the shafts are squared for the mounting upon them of 5 double, valve-operating rocker-arms 19 (Figs. 8 and 9), which are horizontally arranged and formed with squared openings 20 for the reception of the squared upper ends of the shafts to which they are clamped.

10 The ends of these arms respectively mount adjustable contact-screws 21 clamped in place by screws 22 and alternately engaging with the outer ends of the valve-stems 23 of the intake-and exhaust-valves 4 and 5, 15 which may be of any approved construction and arrangement. As shown, these valves are located in cages 24 and 25 and are held in their closed positions by springs 26 in the usual manner. The inlet-valves 4 of 20 the cylinders 27 are alternately operated, as are also the exhaust valves 5 of the same cylinders, due to the rocking of the valve-shafts which are timed to operate in accordance with the operations of the pistons 28 of 25 the said cylinders, as usual in engines of this type.

The squared, projecting, lower ends of the shafts 2 are provided with removable cam-arms 29, the split sleeves 30 whereof having squared openings 31. The projecting inner ends of these arms mount rollers 32 which co-act with cams 33 (Fig. 11) mounted upon the cam-shaft 34, which is located directly below the crank-shaft 35, as clearly shown in Fig. 1, the two-part bearings 36 of the cam-shaft 34 being entirely supported from the upper half 7 of the crank-case so that the lower part 8 of the crank-case may be removed and replaced without disturbing 30 the cam-shaft. As shown, the cam-shaft bearings 36 are suspended by studs 37 passing upward into the upper half 38 of the two-part main-bearings of the crank-shaft 35. I do not, however, limit myself to 40 any one way of suspending the bearings of the cam-shaft from the upper half 7 of the crank-case.

As shown, the cam-shaft 34 is provided at its rear end with a standard, oil-circulating 50 gear-pump 39 by means of which the oil is taken from the bottom of the crank-case and forced into the oil-distributing tube 40 from which it is fed into the dip pans 41, from which it is distributed to all parts of 55 the engine in the usual manner of such engines.

By arranging the rocker-shafts in the vertical plane, they are arranged at right angles with respect to the valve-stems, whereby the 60 friction of the operation of the valves is reduced to the minimum. By suspending the rocker-shafts from their upper ends and suspending their bearing-sleeves in the top of the crank-case, I avoid the necessity of pro-

viding bearings for the rocker-shafts in the 65 lower half of the crank-case, thus enabling me to assemble and adjust the parts of the engine with the lower part of the crank-case removed, at which time the operation of the parts may be seen as they can not be if the 70 crank-case must be in place to support the rocker-shafts. Moreover, the long bearing-sleeves enable the rocker-shafts to be lubricated throughout their length. If desired, the cam-arms of the shafts can be removed 75 without disturbing the same.

I claim:

1. A valve-action for explosive engines, having a two-part crank-case the lower part of which is removable, a crank-shaft located 80 therein, a cam-shaft located therein below the crank-shaft, means for supporting the cam-shaft from the upper part of the crank-case, a rocker-shaft, means connecting the upper end of the said shaft with the intake- 85 and exhaust-valves of the engine, and means connecting the lower end of the rocker-shaft with the cam-shaft, whereby the lower half of the crank-case may be removed and replaced without disturbing the cam-shaft or 90 the rocker-shaft.

2. A valve-action for explosive engines, having a two-part crank-case the lower part of which is removable, a crank-shaft located 95 therein, a cam-shaft located below the crank-shaft, means of supporting the cam-shaft from the upper part of the crank-case, and a cam-operated valve-operating rocker-shaft mounted in the upper half of the crank-case, whereby the lower part of the crank-case 100 may be removed and replaced without disturbing the cam-shaft or the rocker-shaft.

3. A valve-action for explosive engines, having a two-part crank-case of which the lower part is removable, a crank-shaft there 105 in a cam-shaft located below the crank-shaft, means for supporting the cam-shaft independently of the lower part of the crank-case, a bearing-sleeve suspended in the upper half of the crank-case and extending 110 upward above the same and downward thereinto, a rocker-shaft suspended from the upper end of the said sleeve, connection between the projecting upper end of the shaft and the intake- and exhaust-valves of the engine, and a removable cam-arm mounted upon the projecting lower end of the shaft and co-acting with the cam-shaft, whereby the lower part of the crank-case may be removed 115 without disturbing the rocker-shaft 120 and its connections.

In testimony whereof, I have signed this specification in the presence of two subscribing witnesses.

EVERETT S. CAMERON,

Witnesses:

J. HAROLD FLYNN,

GEORGE DUDLEY SEYMOUR,
